UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

VALVE-SPRING-LIFTING DEVICE. BEST AVAILABLE

Application filed May 20, 1920. Serial No. 382,722.

To all whom it may concern:

Be it known that I, WALTER I. TUTTLE, a citizen of the United States and a resident of Providence, in the county of Providence and State of Rhode Island, have invented 5 an Improvement in Valve-Spring-Lifting Devices, of which the following is a specification.

This invention relates to devices for lifting 10 valve springs of the type used in connection with poppet or other valves of internal combustion engines.

One of the objects of this invention is to provide a simple and effective device for 15 lifting valve springs which will be of durable construction and dependable action.

Another object is to provide a device of the above type that will be simple in manipulation and inexpensive to manufacture.

20 Another object of this invention is to provide an efficient valve-spring lifting device which may be readily applied to the desired parts of internal combustion engines and in such manner that accessibility to the parts 25 desired to be operated upon will not be obstructed by the applied lifting device itself.

This invention aims also to provide a device of the above character in which a minimum effort is required to be exerted to accomplish 30 the lifting of the valve springs.

Other objects will be in part obvious and in part pointed out hereinafter.

The invention accordingly consists in the features of construction, combinations of elements and arrangements of parts which will be exemplified in the structure herein described and the scope of the application of which will be indicated in the following claims.

40 In the accompanying drawings in which is shown one preferred embodiment of this invention:

Fig. 1 is a front elevation.

Fig. 2 is a side elevation of a valve-spring lifting device,

Fig. 3 is a plan view with certain parts broken away, and

Fig. 4 is a perspective view of a spring lifting device as applied in use to an internal combustion engine, only such illustrative 50 parts of the latter being shown as are necessary in the application of this device.

Referring now to the drawings, there is shown a pair of members 10 and 11 oppositely disposed from one another and con-

nected together by an upwardly extending saddle portion 12 formed preferably integral therewith. The members 10 and 11 are provided with upwardly extending lugs 13 which may be formed integrally with the members themselves and by up-turning or stamping such lugs from the initial metal plate of which the members 10 and 11 are formed. The members 10 and 11 are furthermore provided with substantially centrally disposed recesses 14—15 respectively and such recesses are preferably made concentrically with the circumferentially disposed lugs 13 positioned at the exterior edges of the members 10 and 11. The purposes of these recesses and the lugs will be hereinafter more clearly described.

Pivottally connected as by the pin 16 to the upper and interior section of the saddle portion 12 is a bell-crank lever composed of 75 the members 17 and 18 making an angle with one another. Pivottally connected as by pin 19 to the end of the member 17 opposite that to which the saddle portion 12 is connected, is a link 20 provided at its 80 lower end with a lateral extension 21 and having its base portion stepped as at 22 for purposes to be hereinafter mentioned. The member 18 of the bell-crank lever is formed at its upper end into a handle 23 so formed 85 that it offers a substantial and convenient area for contact with the hand.

In the use of the device of this invention, reference being had in particular to Fig. 4 of the drawings, it will be noted that the 90 members 10 and 11 are first positioned underneath the valve springs 24 and it will be noted that such valve-springs are securely and effectively centered within the members 10 and 11 by the lugs 13 and that the valve stems 25 are received by the recesses 14—15 and thus permit a positive contact of the members 10 and 11 and the lugs 13 thereon with the lower portions of the springs 24. Having positioned the members 10—11 to 95 engage and receive the valve springs 24, the link 20 is now positioned with its base portion contacting with the lower interior part of the engine casing 26, the link 20 being positioned at a point substantially between 100 the valve stem bearings 27. The provision of a lateral extension 21 on the link 20 and of its stepped base portion 22 permits of the application of the device to various forms of interior engine casing construction 105 110

and permits of the link 20 gaining an effective purchase on such interior casing portions regardless of the exact detailed interior construction thereof. The stepped 5 base portion 22 permits also of the adjustment of the height of the pivot point 19 thereby to extend the range of operation of the device and when used with a block interposed between the casing and the link 10 20, such adjustment is readily made by using any one of the stops desired. The saddle portion 12 extends upwardly between the valve-springs 24 and it will be noted is entirely out of the way and forms no obstruction to the lower parts to which it is 15 desired to gain access. The several parts having been suitably positioned as hereinbefore described, pressure is now exerted upon the handle portion 23 of the lever member 18 in downward direction, whereupon the link 20 forming, as it were, a pedestal or fulcrum for the bell-crank lever permits of the upward movement of the valve-spring engaging members 10 and 11 20 which carry the springs upwardly with them.

It is to be noted that in initially applying this device as hereinbefore described, the link 20 may not always assume a direct vertical position and forms with the member 17 a toggle having its knee at the pivot point 19 connecting the member 17 with the link 20. Application of pressure, however, to the handle portion 23 of the lever 18 results in transmission of such pressure to the knee of the toggle so formed, whereupon the toggle may be operated to any desired extent and substantially straightened out if desired. Accordingly, during such operation 30 the effective leverage of the member 18 is increased as the toggle is straightened out or as the valve spring engaging members 10 and 11 are lifted and hence the effort required to operate against the valve springs 35 decreases in proportion as the valve springs are compressed or lifted.

The application of this device to a pair of valve springs results in many distinctive advantages. The several levers and linkages are at all times substantially between the pair of springs and valve stems and at no time interfere directly with the exposed portion of the valve stems 25 or at no time obstruct the accessibility thereto. Accordingly 40 the pins 28 in the valve stem are readily reached and may be freely withdrawn or replaced. The application of the spring lifting device leaves the lower portions of the valve stems absolutely free and 45 serves in no way to interfere with the freedom of access thereto.

It will further be noted that in acting 50 against a pair of valve springs and by positioning the operative members of the lifting device substantially between the pair of

springs further advantages are obtained. During the entire manipulation the valve spring lifting device is maintained in perfect balance by the reaction of the pair of equal and oppositely disposed springs and a maximum stability of the device during its use is thus maintained throughout. 70

It will be noted that the several parts of the device of this invention are simple in construction and may be readily made of sheet metal and conveniently stamped in the desired forms. Such construction tends not only towards a low cost of manufacture, but also towards great facility in repairing or replacement of any of the parts therein. 75

It will be noted furthermore, that in this invention there has been provided a valve spring lifting device of effective and dependable operation and which during its application and use makes for an unobstructed 80 and maximum accessibility to the several parts of the internal combustion engine to which it is desired to gain access for adjustment or repair. It is to be noted also that in this invention there has been provided a device of the above character in which the several objects have been attained and in which many advantages aside from those already pointed out hereinbefore have been 85 successfully gained. 90

As various possible embodiments might be made of the above invention and as various changes might be made in the embodiments above set forth it is to be understood that all matter herein set forth or shown in the accompanying drawings is to be interpreted as illustrative and not in a limiting 95 sense. 100

I claim:

1. In a device of the class described, in combination, means for engaging a pair of valve-springs and having at its central part a saddle portion extending upwardly between said springs, a bell crank lever pivotally connected at the saddle portion of said engaging means, and means having a stepped base portion pivoted to said bell crank lever forming a pedestal therefor, said lever and said last mentioned means forming a toggle. 110

2. In a device of the class described, in combination, means for engaging a pair of valve-springs and having at its central part a saddle portion extending upwardly between said springs, a bell crank lever having its short arm pivotally connected to said engaging means at the saddle portion thereof, said saddle portion being adapted to accommodate therein said short arm of said bell crank lever, and having its long arm formed into an operating handle, and means pivotally connected to said bell crank lever forming a fulcrum therefor. 115 120

3. In a device of the class described, in combination, a single member formed into two opposite spring engaging means for re- 125 130

ceiving a pair of valve-springs and into a saddle portion extending upwardly between said two spring engaging means, each of said engaging means having a plurality of 5 independent lugs for centering said spring thereon, a bell crank lever having its short arm pivotally connected to said engaging means at the saddle portion thereof, said saddle portion being adapted to accommodate 10 therein said short arm of said bell crank lever, and having its long arm formed into an operating handle, and

means pivotally connected to said bell crank lever forming a fulcrum therefor.

4. In a device of the class described, in 15 combination, means for engaging a valve spring, a lever for moving said engaging means, and a link forming a pedestal for said lever, said link having a stepped base portion for adjusting its height. 20

In testimony whereof, I have signed my name to this specification this 17th day of January, 1920.

WALTER I. TUTTLE.
